UNITED STATES PATENT OFFICE.

THOMAS E. O'BRIEN, OF WATERTOWN, MASSACHUSETTS.

RETURN-ADDRESS ENVELOP.

SPECIFICATION forming part of Letters Patent No. 684,298, dated October 8, 1901.

Application filed December 5, 1900. Serial No. 38,749. (No model.)

To all whom it may concern:

Be it known that I, THOMAS E. O'BRIEN, of Watertown, in the county of Middlesex and State of Massachusetts, have invented certain 5 new and useful Improvements in Return-Address Envelops, of which the following is a specification.

This invention relates to mailing-envelops; and it has for its object to provide means for 10 concealing a return-address marked on an envelop, so that the name of the sender of a communication need not be open to the inspection of the various persons through whose hands the envelop may pass before reaching 15 the addressee.

The invention involves the use of an auxiliary flap covering and concealing the return-address, which flap is designed to be removed by the postmaster should the letter fail of delivery to the addressee, thereby revealing the 20 sender's address and enabling the postmaster to return the letter to the sender.

The invention consists in certain novel features of construction and arrangement in envelops which I shall now proceed to describe 25 and claim.

Of the accompanying drawings, Figure 1 represents a rear elevation of an envelop constructed in accordance with my invention, 30 with both flaps down. Fig. 2 represents a view of the same, with the sealing-flap open. Fig. 3 represents a similar view with both flaps open. Fig. 4 represents a front elevation of the envelop. Fig. 5 represents a rear 35 elevation showing a modification.

The same reference characters indicate the same parts in all the figures.

Referring to the drawings, 1 represents an envelop similar in general to ordinary mailing-envelops—that is, having an unobstructed front face or side 2 for receiving a stamp and the name and address of the person to whom the letter is addressed, a back face or side 3, and a closure or sealing-flap 4, attached to 40 the upper edge of the envelop and adapted to be folded over the opening in the back side of the envelop to cover said opening. Instead of being symmetrical the flap 4 is shown as having one side of its lower edge longer 45 than the other side, for a purpose which will presently appear.

5 is an auxiliary flap, also attached to the

upper edge of the envelop and located outside of the sealing-flap 4, so that when both flaps are down the auxiliary flap will cover 55 the main portion of the sealing-flap. The shorter edge portion of the sealing-flap is shown as uncovered by the auxiliary flap, the latter being complementary in shape to said sealing-flap, so that the two together are symmetrical with respect to the rest of the envelop. The exposed edge of the sealing-flap renders the presence of the latter apparent 60 when both flaps are down and enables the auxiliary flap to be easily removed without 65 tearing off the under flap. On the outer side of the sealing-flap 4 is placed the return address or designation of the sender, its location being such that when the flaps are down the auxiliary flap 5 covers this return-address. 70 The edges of the sealing-flap 4 are preferably gummed in the ordinary manner, and the lower edge of the auxiliary flap 5 is also gummed to enable said lower edge to adhere to the back of the envelop. On the back or 75 outer side of the auxiliary flap 5 may be marked a suitable direction relating to the opening of this outer flap should the letter fail of delivery. When the letter fails to be delivered, the postmaster tears off the flap 5, 80 and thus exposes the return-address on the outside of the sealing-flap.

The fold or crease of the auxiliary flap 5 constitutes a weakened severing-line connecting said flap to the envelop, for, as is well 85 known, an envelop is always weaker at its edges than elsewhere because the sharp bend in the paper tends to break and loosen the fibers.

In Fig. 5 I show a modification in which 90 the sealing-flap 4 and auxiliary flap 5 are both symmetrical with respect to the rest of the envelop, the auxiliary flap being smaller in extent than the sealing-flap and so located as to expose the whole of the lower edge of 95 the latter. Other modifications might be made without departing from the spirit of the invention.

I am aware that it has been proposed prior to my invention to provide an envelop with 100 an auxiliary flap or portion covering a return-address, and I do not claim such structure broadly.

I claim—

1. An envelop having an inner gummed closure to seal said envelop, and an outer independent gummed cover for said closure adapted to be removed without disturbing the
5 said inner closure, the said closure and the cover therefor being foldable together and in the same direction and both across the entrance of the envelop, whereby both may be sealed and the inner closure may be left sealed
10 after the removal of the outer cover.

2. An envelop having a closure provided with two independent gummed sections one of which is adapted to seal the envelop with its contents, and the other having a weakened

severing-line to adapt it to be opened or removed without disturbing the sealing-section, said sections being foldable together and in the same direction and both across the entrance of the envelop whereby the sealing-section may be left sealed across said entrance after the removal of the one having the weakened severing-lines.

In testimony whereof I have affixed my signature in presence of two witnesses.

THOMAS E. O'BRIEN.
